US0D1081676S

(12) **United States Design Patent** (10) **Patent No.:** **US D1,081,676 S**
Sammons (45) **Date of Patent:** **** Jul. 1, 2025**

(54) **DISPLAY SCREEN OR PORTION THEREOF WITH GRAPHICAL USER INTERFACE**

7,171,624 B2 1/2007 Baldwin
 7,461,332 B2 12/2008 Brintzenhofe
 7,516,414 B2 4/2009 Cragun

(Continued)

(71) Applicant: **Salesforce, Inc.**, San Francisco, CA (US)

WO 2010138412 12/2010

(72) Inventor: **Brady Sammons**, Walnut Creek, CA (US)

FOREIGN PATENT DOCUMENTS

(73) Assignee: **Salesforce, Inc.**, San Francisco, CA (US)

(**) Term: **15 Years**

(21) Appl. No.: **29/794,706**

(22) Filed: **Jun. 15, 2021**

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is a front view of a second embodiment thereof. The outermost dashed broken lines in FIGS. 1-2 show a display screen or portion thereof, and form no part of the claimed design. The other dashed broken lines in FIGS. 1-2 show text, graphics, and other elements that form no part of the claimed design.
